(57) **CLAIM**

The ornamental design for a mount body for a solar panel, as shown and described.

DESCRIPTION

FIG. 1 is a top front perspective view of a mount body for a solar panel showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines shown on the bottom perimeter of the mount body for a solar panel in FIG. 7 constitute a boundary of the claimed design and form no part thereof.

1 Claim, 4 Drawing Sheets
